UNITED STATES PATENT OFFICE.

FRANKLIN E. BEATTY, OF PHILADELPHIA, PENNSYLVANIA.

ROPE CUTTER.

Application filed May 8, 1924. Serial No. 711,762.

To all whom it may concern:

Be it known that I, FRANKLIN E. BEATTY, a citizen of the United States, residing in the city and county of Philadelphia, State 5 of Pennsylvania, have invented a new and useful Rope Cutter, of which the following is a specification.

My invention consists of a novel construction of a rope twine or thread cutter, 10 comprising an upper curved bar adapted to fit over the wrist, back or fingers of the hand, of the user said bar being provided with an elastic connection on its underside, and the top of the bar being provided with 15 a cutting blade and guard, which latter are removably secured to said bar, so that said blade is readily accessible or detachable for the purposes of replacement, sharpening and the like.

20 It further consists of other novel features of construction and advantage all as will be hereinafter fully set forth.

For the purpose of illustrating my invention I have shown in the accompanying 25 drawings several forms thereof which are at present preferred by me, since the same have been found in practice to give satisfactory and reliable results, although it is to be understood that the various instrumentalities 30 of which my invention consists can be variously arranged and organized and that my invention is not limited to the precise arrangement and organization of the instrumentalities as herein shown and described.

35 Figure 1 represents a perspective view of a twine cutter embodying my invention.

Figure 2 represents a vertical sectional view on line 2—2 Figure 1.

Figure 3 represents a section on line 3—3 40 Figure 1.

Figures 4 and 5 represent vertical sectional views of a modification to be herein-after referred to.

Similar numerals of reference indicate 45 corresponding parts.

Referring to the drawings:—

1 designates my novel construction of twine cutter, the same comprising a bar 2, having the curved portion 3 adapted partially 50 to encircle the hand or wrist of the user, the outerside of said curved portion having the hook 4, which is engaged by the eye 5 attached to one end of the elastic band 6, whose other end is attached to the end of the bar 2 as indicated at 7. The top of the bar 2 has secured thereto a frame or guard 55

member 8, which may be composed of wires whose lower portions 9 are positioned on each side of the base of the blade or cutter 10. The wires 9 are bent upwardly at the point 11 then deflected backwardly in parallelism with the portions 9 to form a spring guard 12 and then upwardly as at 13, whereby the curved or inclined cutting portion 14 of the blade 10 is positioned directly under the upturned terminal 13, the point 15 forming the apex of the angle between the parts 13 and 14 and serving to effect the cutting or severing of the twine or thread, when applied thereto. I preferably make the blade 10 and the frame or guard member 8 as a unit, and the left hand of the blade and the wires 9 are positioned in a recess 16 under the lip 17, while the right hand end of the blade and said frame 8 are secured within the side walls 18 and the terminal wall 19 by the screw or similar fastening device 20. By this construction upon the removal of the screw 20, the blade 14 is readily accessible 70 for sharpening, replacement or other 80 repairs.

In use the device seen in Figures 1 to 3 is slipped upon the wrist, hand or fingers of the user and is moved against the twine to be cut, so that the severing thereof is effected 85 at the point 15. The elastic 6 causes the device to firmly engage the wrist, hand or fingers of the user, as is evident.

In the construction seen in Figures 4 and 5 the elastic band construction 6 and its 90 mode of attachment is substantially the same as already described, but the construction of the curved bar is slightly different from that seen in Figures 1 to 3. In Figure 4 the curved bar is indicated at 21 and the blade 22 rests directly thereupon, its left hand end 23, being held in position by the clip 24, which is held in place by the screw 25. The top of the blade is held in the slot 26 of the bent plate 27, whose left hand end has 100 the downturned terminal 28, which overlaps the upturned terminal 29 of the bar 21, said terminal 29 being deflected to the left as indicated at 30, and the parts being held in assembled position by the screw 31. 105 In Figure 5, I have shown the bar 32 as provided with a right hand upwardly deflected portion 33 and a laterally deflected lip 34, under which are located the ends 35 of the guard 36, said ends 35 passing through 110 the wall 33 and the parts being held in assembled position by the screw 37, whose

lower end is threaded into the plate 38, by which means the end 39 of the elastic band 6 is secured in position. To the upper left hand portion of the bar 32 is secured the strip 40 which has the slot 41 at its right hand end which receives the end of the blade 42, which is secured in position by the transverse screw 43. In this construction the blade and the guard are readily removable 10 on removing the screws 43 and 37, while in the construction seen in Figure 4, the blade is readily accessible on removing the screws 25 and 31.

It will be seen that in all the embodiments of my invention, the blade is readily removable, and its upper edge as well as its joint, is guarded and protected at all times, so that only the cutting edge 14 is exposed as is evident. The guard member in all the 20 embodiments of my invention straddle the upper cutting edge of the blade and has its terminal above the exposed edge of the blade projected upwardly. The guards seen in Figures 1, 2, 3 and 6 are preferably formed 25 of wire, while the guard seen in Figure 4 is preferably formed of a piece of slotted sheet metal.

My novel device is applicable not only for cutting twine and other thread but also for 30 ripping seams, slicing fabrics into rags, and for other analogous uses.

The purpose of the spring guard 12 is so 35 that when a piece of rope is presented to the cutting portion 14, the said part 12 will yield sufficiently to permit rope being introduced to said cutting portion and at the same time provide sufficient pressure upon the rope to hold it taut against the cutting portion.

Having thus described my invention what

I claim as new and useful and desire to secure by Letters Patent, is:-

1. In a rope cutter, an elongated, curved upper bar, an elastic band having its ends detachably connected to the ends of said bar, a cutting blade positioned upon the top 45 of said bar and extended throughout the major portion of its extent, a guard to receive the pointed end of said blade and an upper guard for the upper edge of said blade and having its terminal above the exposed 50 edge of said blade deflected away therefrom.

2. In a rope cutter, an elongated, curved upper bar, an outer hook on one end thereof, a band having one end connected to said hook, and its opposite end connected to the 55 opposite end of said bar, a cutting blade positioned on the top of said bar and extended throughout the major portion of its extent, and a guard member detachably mounted on said frame and having its end above the 60 exposed edge of said blade upwardly deflected.

3. In a rope cutter, an elongated, curved upper bar, having one side extended downwardly well below the opposite end thereof, 65 an outer hook upon said curved end, an elastic band having one end connected to said hook and the other end to the opposite end of said bar, a cutting blade positioned on the top of said bar, extended throughout the 70 major portion of its extent, a guard member for upper edge of said blade, and having its terminal above the exposed edge of said blade projected upwardly and means upon 75 said extended bar portion to receive the opposite end of the guard and the pointed end of the blade.

FRANKLIN E. BEATTY.
